UNITED STATES PATENT OFFICE.

STEPHEN DE ORLO, OF LANSING, MICHIGAN, ASSIGNOR TO GENERAL MOTORS CORPORATION, OF DETROIT, MICHIGAN, A CORPORATION OF DELAWARE.

HOOD CATCH.

Application filed December 8, 1924. Serial No. 754,604.

To all whom it may concern:

Be it known that I, STEPHEN DE ORLO, a citizen of the United States, and a resident of Lansing, county of Ingham, and State of Michigan, have invented certain new and useful Improvements in Hood Catches, of which the following is a full, clear, concise, and exact description, such as will enable others skilled in the art to which the invention relates to make and use the same, reference being made therein to the accompanying drawings, which form a part of this specification.

My invention relates to hood door latches designed for use with automobiles to hold the doors of the hood which encloses the engine closed, with the lower free edge thereof spring pressed against a stationary stop or jamb carried by the frame of the vehicle; and the object or end in view in my invention is to provide an improved latch for the purpose stated wherein the free lower edge of the door will be drawn downward by a spring, and at the same time forced inward 25 and against the stop by a second spring; the second mentioned spring (or rather an integral portion or extension thereof) serving also as a support for a spring actuated hold down member having a hook for engaging an abutment carried by the door to accomplish the holding down action, and the lower end of which is so shaped, as by providing said end with a transversely extending cylindrical eye, that a pivotal connection between the latch as a whole and a fixed support therefor carried by the frame of the vehicle may be established.

With the above and other objects of invention in view my invention consists in the improved hood door latch illustrated in the accompanying drawing, described in the following specification, and particularly claimed in the concluding claims; and in such variations and modifications thereof, within the scope of the concluding claims, as will be obvious to those skilled in the art to which my invention relates.

In the drawing accompanying and forming a part of this specification and wherein the preferred embodiment of my invention is illustrated:

Figure 1 is a fragmentary end view, most-

ly in section, showing my improved hood door latch and illustrating the use thereof for holding a hood door closed. 55

Figure 2 is a view showing the parts shown in Figure 1 in side elevation.

Figure 3 is a view similar to Figure 1 but showing the parts in another position; the hood door being latched closed in Figure 1, 60 and unlatched in Figure 3.

Figure 4 is a view showing a slightly modified form of a detail of my invention.

Referring now to the drawing, the reference numeral 5 designates a hinged hood door to be held closed, 6 a fixed jamb or stop against which the lower edge of the door is to be held, and 7 a suitable fixed support which may be one of the two longitudinally extending side frame members of the vehicle. The construction of the door and stop, and the character of the support as regards additional functions performed thereby are, however, quite immaterial, as my invention is in no way concerned with these members otherwise than to require their presence in order that the latch may function in the manner contemplated. The numeral 8 designates an intermediate connecting member whereby and through which my improved hood door latch is pivotally connected with the fixed support 7 or its equivalent, the said member being shown as in the form of a stirrup having a threaded pin 9 depending through a hole in the bar 7, and held in place by a nut 10. My invention, however, regarded in its broader aspect, is independent of the particular form of intermediate member employed for effecting a pivotal connection between the principal operative elements thereof to be next described and the frame or equivalent fixed support serving the purpose of the bar 7; and various specific forms of connecting member other than the particular form illustrated, may be employed. 90

The reference numeral 11 designates a spring arm made from resilient material such as steel, and which is preferably of uniform width throughout its length so that it can be made from flat bar stock; and 12 is a block, usually made of rubber, fastened to the upper end of the spring arm and which block is pressed against the door by 100

the action of the spring arm when the door is held closed, as shown in Figure 1, thereby yieldably pressing the lower edge of the door against the stop 6 at such times. When 5 the door is unlatched as shown in Figure 3 the arm and block move away therefrom, so that the door can be lifted and opened, as will be appreciated.

The numeral 13 designates a stem the 10 lower end of which is fixedly fastened to the lower part of the spring arm 11, and which stem extends upwardly alongside said arm. This stem supports a spring actuated hold 15 down member which is movable longitudinally of the stem, and which may take various specific forms; but which is shown as comprising a hollow barrel 14 slidable upon the stem and which is pressed downward by a spring 15 housed therein; and acting be- 20 tween an abutment 16 and a head at the upper end of the stem. The hold down member is provided with a handle 17 at its upper end whereby it may be lifted against the action of the spring, and with a hook 25 18 arranged to engage a fixed abutment 19 carried by the door to thereby hold the same closed. The spring arm 11 is continued be- 30 yond the point of connection between the same and the lower end of the stem 13, and is so shaped at its lower extremity as to facilitate the pivotal connection of said lower end to a fixed support such as is provided by the connecting member 8; said spring arm being shown as having a trans- 35 versely extending cylindrical barrel or eye 20 at its extremity, formed by curling the said lower end, through which and through holes in the member 8 a pivot pin 21 extends. In Figures 1, 2 and 3 the lower end of the 40 spring arm is bifurcated, and receives a central upwardly extending portion of the stirrup 8; whereas in Figure 4 the spring arm fits between two side arms 22 of an equivalent stirrup 23.

45 The lower end of the stem 13 is prefer- ably fastened to the spring arm 11 by pro- viding the latter with a U-shaped loop at 24 (by the use of suitable bending dies, prior to the assembling of the parts as will be ap- 50 preciated) having aligned upper and lower holes through which the lower end of the stem may pass; and by flattening the end of the stem, as indicated at 25, after the said lower end has been inserted into the holes aforesaid. This method of fastening the 55 parts together provides a construction wherein excessive resistance to the pulling out of the stem from the holes in the spring arm is secured, and at the same time provides a 60 construction wherein wobbling of the stem is prevented because of the spaced apart supports at the sides of the stem provided by the walls of the holes through which its lower end extends.

65 Having thus described and explained my

invention, I claim and desire to secure by Letters Patent:

1. A hood door latch of the class described comprising a spring arm having a door engaging block at its upper end, and the lower end of which is pivotally connected with a fixed support; a stem fixedly secured to said arm adjacent the lower end thereof, and extending upwardly from said lower end alongside said arm; and a spring actuated hold down member carried by said stem and movable longitudinally thereupon, and having a hook adapted to engage a fixed abutment carried by a hood door. 70

75 2. A hood door latch of the class described comprising a spring arm having a door engaging block at its upper end, and the lower end of which is provided with a transversely extending cylindrical eye for providing a pivotal connection between said lower end and a fixed support; a stem fixedly secured to said arm adjacent the lower end thereof, and extending upwardly from said lower end alongside said arm; and a spring actuated hold down member carried by said stem and movable longitudinally thereupon, and having a hook adapted to engage a fixed abutment carried by a hood door. 80

85 3. A hood door latch of the class described comprising a spring arm of substantially uniform width throughout its length and having a door engaging block at its upper end, and the lower end of which is curled to provide a transversely extending cylindrical eye for providing a pivotal connection between said lower end and a fixed support; a stem fixedly secured to said arm adjacent the lower end thereof, and extending upwardly from said lower end alongside said arm; and a spring actuated hold down member carried by said stem and movable longitudinally thereupon, and having a hook adapted to engage a fixed abutment carried by a hood door. 90

95 100 4. A hood door latch of the class described comprising a spring arm having a door engaging block at its upper end, and the lower end of which is bent to provide a U-shaped loop and is provided with means below said loop whereby said arm may be pivotally connected with a fixed support; a stem extending alongside said arm and the lower end of which extends through holes in opposite sides of said loop, and is fixedly secured to said arm; and a spring actuated hold down member carried by said stem and movable longitudinally thereupon, and having a hook adapted to engage a fixed abutment carried by a hood door. 110

115 120 125 5. A hood door latch of the class described comprising a spring arm having a door engaging block at its upper end, and the lower end of which is bent to provide a U-shaped loop and is provided with a transversely extending cylindrical eye below said loop; 130

a fixed support having a pivot pin extending through said eye; a stem extending alongside said arm and the lower end of which extends through holes in opposite sides of said loop, and is flattened between said arms to thereby fasten it to said arm; and a spring actuated hold down member

carried by said stem and movable longitudinally thereupon, and having a hook adapted to engage a fixed abutment carried by a hood door.

In testimony whereof I affix my signature.

STEPHEN DE ORLO.
